UNITED STATES PATENT OFFICE.

BENNIE L. BECKNER, OF ANDERSON, INDIANA, ASSIGNOR OF ONE-THIRD TO HOWARD WITT AND ONE-THIRD TO FRANK H. SCHLATER, BOTH OF ANDERSON, INDIANA.

COMBINATION LOCK AND SWITCH.

1,229,211.

Specification of Letters Patent. Patented June 12, 1917.

Application filed September 23, 1916. Serial No. 121,707.

To all whom it may concern:

Be it known that I, BENNIE L. BECKNER, a citizen of the United States, residing at Anderson, in the county of Madison and State of Indiana, have invented certain new and useful Improvements in Combination Locks and Switches; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a combined lock and switch adapted for use on automobiles, motorcycles, motor-boats, and other transportation means and designed to place the operation of the switch which opens or closes a circuit under the control only of the person familiar with the combination of the particular permutation lock applied to the switch and thus guard against the unauthorized use of the mechanism to which the combined lock and switch is applied. The object of the invention is to provide a lock and switch of the character mentioned which will embody simplicity and efficiency without liability of easily getting out of working order, which may be made within reasonable limits as to cost of construction, and may be readily operated without skilled knowledge on the part of the initiate or instructed. To the accomplishment of the foregoing and such other objects as may hereinafter be made to appear the invention consists in the features hereinafter particularly described and then sought to be clearly defined by the claims reference being had to the accompanying drawing forming a part hereof, and in which:

Figure 1 is a front elevation or face view of the device;

Fig. 2 is a vertical longitudinal section through the same;

Fig. 3 a cross section on the line 3—3 of Fig. 2, looking in the direction of the arrows, and showing one position of the switch;

Fig. 4 a cross section on the line 4—4 of Fig. 2, looking in the direction of the arrows, showing another position of the switch;

Fig. 5 a perspective of the switch permutation plate;

Fig. 6 a perspective of the switch bar or arm.

In the drawing the numeral 1 designates a box or shell preferably formed of some suitable insulating material upon which is mounted the shell or jacket 2 formed of suitable material preferably aluminum, and having a face-plate 3 upon which is inscribed divisions, in the present instance, represented by the numerals ranging from zero (0) to 55, or otherwise. Within the shell or jacket is a dial-plate 4, rotatable therein, and inscribed on its face with divisions represented by numerals varying from zero (0) to 55, or otherwise, corresponding to the like divisions on the face of the inclosing jacket or shell. This rotatable dial is mounted upon a bushing or sleeve 5, preferably made of some suitable insulating material, and held thereto by friction or otherwise so as to move therewith, the inner end of the sleeve or bushing projecting within the boxing or shell 1 and being bifurcated or slotted so as to form oppositely disposed prongs 6. A spindle 7 extends through the bushing or sleeve 5 so as to be free to turn therein and is provided with a thumb piece or head 8 bearing against one end of the bushing 5, and with a collar or shoulder 9 to bear against the other end of the bushing and its inner end is formed with screw threads 10 and receives a bar or arm 11 which for convenience will be designated a switch arm and is threaded onto the threaded portion of the spindle, the reduced end of the spindle being stepped in the base of the box or casing 1.

The switch arm carries contact plates or members 12, and fits within the slot of the bushing and may be moved back and forth by turning the spindle and will be guided by the prongs of the bushing so long as the bushing is stationary, and by turning the bushing in connection with the dial plate the switch arm may be rotated for the purpose hereinafter appearing. The base of the box 1 is provided with the posts 13 of the circuit electric conductors 14 and 14^a, the contact ends of which posts fit within sockets 15 of the box base. Overlying the inner face of the base of the box is a plate 16, which for convenience, and because its

position will determine or control the making as well as the prevention of contact between the switch arm and terminals of the electric conductors, will be designated as a 5 permutation plate. This plate is mounted, preferably loosely, upon the reduced end of the spindle 7, so as to be movable or rotatable, and is formed with openings 17, which may be in the form of slots, that may be 10 brought into register with the sockets 15 so as to permit passage of the members 12 of the switch bar to make contact with the terminal posts of the electric conductors when the circuit is to be closed. This 15 permutation plate is also provided with a stud or pin 18 with which the switch arm or bar may come in contact when moved or turned so as to shift or change the position of the 20 permutation plate to bring its openings into register with the terminal sockets to enable the switch arm or bar to make contact with the terminal posts to close the circuit, and also to bring said openings out of register with the sockets so as to prevent contact and 25 closing of the circuit at other times. The switch arm or bar and the stud or pin of the permutation plate are so positioned in relation to each other that the movement of the switch arm to a certain or predetermined 30 extent or degree in one direction is necessary to bring the openings of the permutation plate into register with the terminal post sockets, and then its movement to another certain or predetermined extent or 35 degree is necessary to bring the contact members of the switch arm into register with the openings of the plate and the socket terminals so that then the members of the switch arm may be moved into contact with 40 the conductor terminals so as to close the circuit. In other words there is effected a certain combination made up of a certain relation of the pin of the permutation plate to the switch bar and the switch bar to the 45 openings in the plate and of the movement of the switch bar to a certain or predetermined extent in certain directions which must be observed and followed in order to make contact to establish or close the operating 50 circuit and unless the movements are followed to meet the existing conditions no circuit can be established or closed, and thus a combination lock for the switch controlling the making of the circuit is provided. 55 This combination may be different for each switch put out, and by changing the position of the stud or pin of the permutation plate another combination is formed, and thus as many different combinations may be 60 formed as changes are made in the position of the pin. The combination, selected for illustration, in the drawing is zero (0) and 21; the position of the pin of the permutation plate stands in relation to the contact 65 openings in the plate as shown, and the switch arm stands parallel to or coincident with the markings 0—30 on the rotatable dial. Under such combination if it be desired to unlock the switch and operate it for closing circuit, the rotatable dial is 70 turned from left to right, whatever be the position of the switch arm and zero (0) on such dial, until zero (0) on the dial is brought coincident with zero (0) on the stationary dial, during which rotation one of 75 the contact members on the switch arm will be brought into engagement with, or pick up, the stud or pin of the permutation plate whenever for the time being it may be in the path of travel of the switch arm; then the dial is 80 continued in its rotation to the right from zero (0) on the stationary dial until zero of the rotatable dial coincides with the numeral designation 21 on the stationary dial, 85 whereupon the parts will stand in the position illustrated in Fig. 4 with the contact openings in the permutation plate registering with the terminal post sockets in the base of the switch box; then the rotatable dial is turned to the left until zero of such 90 dial coincides again with the zero designation on the stationary dial, thus bringing the switch arm parallel to or coincident with the designations 0—30 on the stationary 95 dial and the contact members 12 in register with the openings or slots in the permutation plate and the terminal post sockets; then the threaded spindle 7 is turned to the left so as to feed forward the switch arm 100 between the prongs of the dial bushing and bring its contact members into contact with the terminal posts of the conductor wires and close the circuit. When it is desired to break the circuit and lock the switch, the threaded spindle is turned to the right as 105 indicated by the arrow in Fig. 1 to withdraw the switch arm until its contact members are free from the permutation plate, and then the rotatable dial is given a throw 110 or turn, say to the right, so as to move the switch arm in the direction indicated by arrow in Fig. 2 until its contact members are out of register with the openings in the permutation plate, and its throw may be to such an extent as to strike the pin of the 115 permutation plate and shift the plate to move its openings from register with the terminal post sockets. The switch is then in practically a locked condition so that it cannot be operated to close circuit except 120 by a person knowing the particular combination provided for the particular switch and the manner of operating the parts to set the combination for closing the circuit. The switch formed as described is made up of 125 comparatively few parts, simple to operate by one made aware of the combination and proper manipulation of the parts, and affords a positive protection against operation of the switch to close the circuit for 130

operation of the machine or other object to which the switch is applied, by the uninformed and unauthorized individual.

I have illustrated and described the invention in its simplest form and in its preferred construction of parts but changes can be made to suit the particular application of the device desired and essential features of the invention retained.

10 Having described my invention and set forth its merits what I claim is:—

1. A combination lock and switch comprising electrical terminal contacts, a permutation plate for covering the terminal contacts having openings to register with said contacts, and provided with an abutment stud, a switch bar slideable to make contact with the terminal contacts and rotatable in the path of the abutment stud of the permutation plate, means for rotating the switch bar to engage the permutation plate stud, to bring the openings of the plate into register with the terminal contacts, means for sliding the switch bar to make contact with the terminal contacts, and designating means for indicating predetermined movements of the permutation plate and switch bar for adjustment of the parts to operative positions.

2. A combination lock and switch comprising electrical terminal contacts, a permutation plate for covering the terminal contacts, a switch bar for moving the permutation plate to uncover the terminal contacts and make contact with the terminal contacts, and means for operating the switch bar to effect movement of the permutation plate and make connection with the terminal contacts.

3. A combination lock and switch comprising electrical terminal contacts, a permutation plate for covering the terminal contacts and provided with an abutment stud, a switch bar provided with members

for engagement with the stud of the permutation plate to uncover the terminal contacts and to make connection with the terminal contacts in a predetermined position, and means for operating the switch bar.

4. A combination lock and switch comprising electrical terminal contacts, a permutation plate for covering the terminal contacts formed with openings for exposing said contacts and provided with an abutment stud, a switch bar for engagement with the stud of the permutation plate for moving the plate to uncover the terminal contacts and for making connection with said terminals, a rotatable dial operatively connected with the switch bar to rotate the bar, means for moving the switch bar into and out of connection with the terminal contacts, and means for determining predetermined movements of the permutation plate and switch bar for bringing the parts into position for unlocking the switch and closing a circuit through the terminal contacts.

5. A combination lock and switch comprising electrical terminal contacts, a permutation plate for covering the terminal contacts formed with openings for exposing said contacts and provided with an abutment stud, a switch bar for engagement with the stud of the permutation plate for moving the plate to uncover the terminal contacts and for making connection with said terminals, a rotatable dial operatively connected with the switch bar to rotate the bar, and a spindle formed with a threaded portion upon which the switch bar is mounted for moving the bar into and out of connection with the terminal contacts.

In testimony whereof I affix my signature in presence of two witnesses.

BENNIE L. BECKNER.
